UNITED STATES PATENT OFFICE.

JOHN P. FOLEY, OF COLUMBUS, KANSAS.

RAIL-FASTENER.

1,213,856.

Specification of Letters Patent. Patented Jan. 30, 1917.

Application filed August 31, 1916. Serial No. 117,938.

To all whom it may concern:

Be it known that I, JOHN P. FOLEY, a citizen of the United States, residing at Columbus, in the county of Cherokee and 5 State of Kansas, have invented certain new and useful Improvements in Rail-Fasteners, of which the following is a specification.

This invention relates to railway ties, and has for its primary object to provide a 10 simple, inexpensive, and improved means for attaching railway rails to the tie quickly and expeditiously, and in such manner as will prevent accidental displacement of the rails, such as rail spreads and the like.

15 A further object of the invention is to provide a device of this character which holds the rails positively against movement toward or away from each other, and which also acts as a support or binder for the 20 tie.

With these objects in view, together with others which will appear as the description proceeds, the invention resides in the novel formation, combination and arrangement of 25 parts, all as will be described more fully hereinafter, illustrated in the drawings, and particularly pointed out in the claims.

The invention will be best understood by 30 reference to the accompanying drawings, wherein:—

Figure 1 is a sectional view taken through the rails of a conventional form of track, and illustrating in connection therewith, a 35 tie constructed and arranged in accordance with the invention; Fig. 2 is a plan view of the device shown in Fig. 1; and Fig. 40 3 is an enlarged sectional view taken through the rail and a portion of the tie and binder.

Referring now more particularly to the drawings, 4 indicates a conventional form 45 of railway tie, and 5 the railway rails supported thereon.

The tie may be formed of wood or concrete and is provided with an elongated rail retaining member 6, the latter extending throughout the length of the tie and upon the lower face thereof, and extending 50 at its ends up and over the extremities of the tie to lie upon the upper face of the latter. This strap member is arranged preferably intermediate the longitudinal edges of the tie, and is relatively narrow throughout its length. The extremities of the retaining member are widened as shown in

Fig. 2, and are bent upwardly and angularly to conform to the configuration of the outer base flange and web of the rail. This widened portion of the retaining member, indicated at 7, prevents outward shifting or spreading movement of the rails, and also performs the function of the fish plates now generally used in effecting a connection between the ends of the adjacent rails.

60 Bolts 8 extend through elongated openings in the fish plate portion of the retaining member and through the rail to firmly bind the latter to the former.

The rail retaining member is secured to 65 the tie 4 by means of bolts 9, the latter passing entirely through the tie and through the upper and lower portions of the rail retaining member.

Associated with a tie of the above construction for preventing the rails moving inwardly of the tie or toward each other, is a rail clamp 10. This clamp is formed of a metallic bar of substantially the same width as the member 6, and is provided with 70 fish plate portions 11 at its extremities for engaging against the inner faces of the opposing rails. The rail clamp lies flat upon the upper face of the tie, and is secured thereto by bolts 12, the latter extending through 75 the tie and also through the retaining member 6 secured to the under face of the same. The bolts 8 extending through the fish plate portions 7 of the retaining member 6 also pass through elongated openings in the fish 80 plate portions 11 of the rail clamp, and it is obvious from this construction that the rail is firmly bound to the retaining member and clamp. When it is desired to remove the rails, the bolts 12 at the ends of 85 the rail clamp may be withdrawn, and the clamp swung upon the intermediate bolt. The rails may be then replaced or readjusted, whereupon the rail clamp may be 90 swung back to operative position and secured at its ends by the bolts 8 to the rails, and to the tie by the bolts 12.

95 From this construction, it is obvious that I have provided an extremely simple, inexpensive and yet thoroughly efficient 100 means for securing railway rails to ties. The clamp and retaining members operate as binders for strengthening the tie and lending rigidity thereto. The members 6 and 10 perform functions of preventing 105 110

the rails moving toward or away from each other and also securing the ends of adjacent rails.

While the above is a description of the preferred embodiment of the invention, it is obvious that various changes in the minor details of construction and arrangement of parts may be resorted to, if desired, without departing from the spirit of the invention or exceeding the scope of the claims.

What is claimed is:

1. In a device of the class described, a tie, a retaining member comprising a relatively narrow metallic strap secured to the under face of the tie and extending at its extremities inwardly from the ends of the tie and upon the upper face thereof, the extremities of said strap being of greater width than the body portion of the same and being adapted to engage and snugly fit the web of a rail; a rail clamp comprising a strip of metal secured to the upper face of the tie and between the extremities of said retaining member, the ends of said clamp being widened and adapted to snugly engage the webs of the opposing rails, and

Copies of this patent may be obtained for five cents each, by addressing the "Commissioner of Patents Washington, D. C."

the said widened portions of said clamp and retaining member being provided with aligned openings, substantially as described.

2. In a device of the class described, a tie, a rail retaining member comprising a metallic strap extending longitudinally of the tie upon the under face thereof and projecting inwardly from the opposite ends of said tie upon the upper face of the same, the extremities of said member being widened and bent to form fish plate portions, a rail clamp secured to the upper face of said tie, the ends of said clamp being bent upwardly and angularly to provide fish plate portions for engagement with the inner faces of railroad rails, and bolts adapted to extend through the fish plate portions of said retaining member and said clamp and through rails held thereby, substantially as described.

In testimony whereof I affix my signature in presence of two witnesses.

JOHN P. FOLEY.
